UNITED STATES PATENT OFFICE

2,190,926

TRANSMISSION MECHANISM

Joseph F. Joy, Pittsburgh, Pa., assignor to Sullivan Machinery Company, a corporation of Massachusetts

Application January 29, 1936, Serial No. 61,321
Renewed November 28, 1938

16 Claims. (Cl. 74—125.5)

This invention relates to transmission mechanisms, and more particularly to improvements in a transmission mechanism of the type embodying high and low speed driving means, the low speed drive variable through a wide range, together with improved means for controlling the high and low speed driving means.

The improved transmission mechanism is particularly adaptable to the feeding means of coal cutting machinery, and particularly to coal cutting machines of the flexibly fed, continuous cutter, floor cutting type which is movable over the mine floor during operation of the machine and which employs a flexible haulage means on the machine for feeding the machine over the mine floor. In the feeding of coal cutting machinery of the above character, it is necessary to provide a powerful feed, but at the same time it is desirable to provide means for precluding the possibility of the exertion of an excessive feeding force resulting in overloading of the machine. It is also desirable to set the low feeding speed to suit the particular conditions of cutting and then to permit release of the low speed drive and connection of the high speed drive, and thereafter to return to the low speed drive without the necessity of resetting the latter; and it is further desirable to provide but a single operating member for the controlling means of both the high and low speed drives.

An object of this invention is to provide an improved transmission mechanism having embodied therein means for accomplishing the desirable features above enumerated. Another object is to provide an improved transmission mechanism having improved high and low speed driving means and improved means for varying the low speed drive through a wide range of speeds between zero and a predetermined maximum low feeding speed. Yet another object is to provide selective intermittent or continuous low speed drive. A further object is to provide an improved transmission mechanism having a predetermined high and variable low speed driving means, improved means for varying the low speed drive, and improved controlling means for both drives. A still further object is to provide, in a transmission mechanism of the above character, a low speed variable drive embodying an intermittent transmission device in the form of a friction clutch through which power is transmitted to effect drive, and having improved means for intermittently releasing the clutch at timed intervals, together with means for varying the intervals of clutch release. A further object is to

provide an improved load-limiting means for the variable low speed drive, whereby the low speed drive clutch is adapted to slip automatically upon overload thereof. Still another object is to provide an improved transmission mechanism having predetermined high and variable low speed drives, and improved controlling means therefor whereby the drive may be quickly shifted from low to high speed drive, and then back to low speed drive without resetting the driving speed of the low speed drive and under the control of but a single operating member. These and other objects and advantages of the invention will, however, hereinafter more fully appear.

In the accompanying drawings, there is shown, for purposes of illustration, one form which the invention may assume in practice.

In these drawings,

Fig. 1 is a plan view of a coal cutting machine having embodied therein the illustrative form of the improved transmission mechanism.

Fig. 2 is an enlarged horizontal sectional view, with parts shown in plan, of the feeding end of the machine shown in Fig. 1.

Fig. 3 is a cross sectional view taken substantially on line 3—3 of Fig. 2.

Fig. 4 is a detail sectional view taken substantially on line 4—4 of Fig. 3.

Fig. 5 is a cross sectional view taken substantially on line 5—5 of Fig. 2.

Fig. 6 is a plan view of the transmission mechanism shown in Fig. 2, with parts broken away in section.

Fig. 7 is a cross sectional view taken substantially on line 7—7 of Fig. 2.

Fig. 8 is a detail sectional view taken substantially on line 8—8 of Fig. 6.

Fig. 9 is a detail sectional view taken substantially on line 9—9 of Fig. 6.

Fig. 10 is a detail sectional view taken substantially on line 10—10 of Fig. 6.

In this illustrative embodiment of the invention, the improved transmission mechanism is shown embodied in the feeding means of a coal mining machine of the flexibly fed, continuous cutter, longwall type, generally comprising a body 1 having a smooth bottom surface 2 adapted to rest upon and slide in any direction over the mine floor. Pivotedly mounted at 3 on one end of the machine body for horizontal swinging movement with respect thereto about a vertical axis, is an elongated plane cutter bar 4 carrying on its margin for circulation thereabout, an endless cutter chain 5. As is common in mining machines of the type disclosed, the cutter bar 4 is swingable

into different angular positions relative to the machine body and is adapted to be locked in its different positions by any suitable locking means. The machine is fed over the mine floor during maneuvering of the machine at a relatively high machine-moving speed, and during the cutting operation at variable low speeds, by means of a haulage means on the machine, comprising a horizontal cable winding drum 6 arranged at the 5 opposite end of the machine body for rotation about a vertical axis and having wound thereon a flexible feeding cable 7. Arranged at opposite sides of the feeding drum are horizontal guide sheaves 8 for guiding the feeding cable 7 with 10 respect to the feeding drum 6 during the various operations of the machine. The feed cable 7 is connectible to the cutter bar 4 in a usual manner, and when the bar locking means is released, the feed cable may be wound in by the feed drum to 15 effect swinging of the cutter bar about its pivot, from the dotted-line moving position indicated in Fig. 1 to the right-angle cutting position indicated in full lines in that figure. During the feeding of the machine along the coal face, the feed cable is extended from the feed drum in the manner indicated in full lines in Figs. 1 and 2, and is connected at its free end to a suitable anchor located in advance of the machine, near the coal face; and as the feed cable is wound in, the 20 machine is fed bodily over the mine floor to cut a horizontal kerf in the mine wall, in a manner well understood by those skilled in the art. The cutter chain 5 is driven, through suitable connections not shown, by a motor 9, herein preferably of the reversible type, having its power shaft 10 horizontally disposed and extending longitudinally of the machine body.

Now referring to the improved transmission mechanism between the motor power shaft and the feed drum for rotating the latter in one direction through a wide range of low speeds and in the opposite direction at a predetermined high machine-moving speed, it will be noted that keyed to the motor power shaft 10 is a motor pinion 11 (Fig. 2) meshing with a spur gear 12 keyed to a horizontal shaft 13 extending longitudinally of the machine body and suitably journaled within the feed frame section 14. Fixed to and rotatable with the shaft 13 is a spur gear 15 meshing with a spur gear 16, herein constituting the high speed terminal driving element of the high speed drive. The hub 17 of the gear 16 is suitably journaled within the feed frame section and is connectible by a multiple disc clutch 18 of a usual design to a horizontal, longitudinally extending, tubular shaft 19, herein arranged parallel with the shaft 13 and likewise suitably journaled within the feed frame section. The hub 17 of the gear 16 is keyed to a transmission shaft 20, herein extending centrally through the shaft 19 and suitably journaled within the feed frame section. Keyed to the end of the shaft 20 remote from the spur gear 16, is a spur gear 21 meshing with a spur gear 22 keyed to a horizontal, longitudinally extending shaft 23, herein arranged parallel with the shaft 20 and likewise suitably journaled within the feed frame section. Secured to and rotatable with the shaft 23 is a spur gear 24 meshing with an intermediate gear 25, 20 in turn meshing with a spur gear 26 journaled on the shaft 19 in coaxial relation with the high speed terminal gear 16 and rotatable in the opposite direction with respect thereto. The spur gear 26 herein constitutes the low speed terminal driving element of the low speed drive, and is

connectible by a multiple disc clutch 27 of a usual design, to the shaft 19. Preferably formed integral with the tubular shaft 19 is a worm 28 meshing with a worm wheel 29 (see Fig. 3) keyed to a vertical shaft 30, herein suitably journaled within the feed frame section. Secured to and rotatable with the shaft 30 is a spur gear 31 meshing with an internal gear 32 formed on the feed drum 6.

Suitable means for loading the disc clutches 18 and 27 of the high and low speed drives is provided, including means for effecting selective intermittent or continuous loading of the low speed clutch 27 and for further providing a maximum load limit. This improved clutch-loading means comprises a cam 35 formed on the sleeve-like clutch housing 36 integral with the low speed terminal gear 26, and engageable with the surface of this cam is a plunger 37 guided in a bore 38 formed in a bracket 39 supported within the feed frame section. The opposite end of this plunger is engageable with a horizontal lever 40 pivotally connected at 41 on a vertical axis to an adjustable, horizontally swingable bell crank 42, the latter herein providing an adjustable fulcrum for the lever 40. This bell crank is pivotally mounted at 43 on a vertical axis within the feed frame, and has its arm 44 engageable by an adjusting screw 45 threaded within the end wall of the feed frame section and having a suitable operating handle 46. Pivotally connected at 47 to the lever 40, between its end engageable with the plunger 37 and its pivotal connection 41, is a horizontal rod 48, herein extending transversely across the feed frame and pivotally connected 30 at 49 at its opposite end to a lever 50. The lever 50 is horizontally swingable about a vertical axis at 51; and pivotally mounted on an axis coinciding with axis 51, at 52, is a horizontally swingable shipper yoke lever 53. For adjusting the angular relation of the shipper yoke lever 53 about its pivot with respect to the lever 50, there are formed on the lever 50 upstanding lugs 54, 54 each having threaded therein adjusting screws 55 engaging the opposite sides of a lug 56 formed on the shipper yoke lever 53. By adjusting the screws 55, the shipper yoke lever may be set in the proper predetermined angular position relative to the lever 53. The shipper yoke lever 53 is engageable with a shipper ring 57 axially slidably mounted on the shaft 19 for pressing the discs of the low speed clutch 27 together to apply the latter. The high speed clutch 18 is provided with a similar shipper ring 58 axially slidable on the shaft 19 to press the discs of the high speed clutch together to apply the latter; and engageable with this shipper ring 58 is a shipper yoke lever 59 pivoted for horizontal swinging movement at 60. Pivotally connected to the shipper yoke lever 59 at 61 is an adjustable link 62 having a turnbuckle adjusting block 63, the link in turn being pivotally connected at 64 to the shipper yoke lever 59. This link connects the shipper yoke levers together for simultaneous swinging movement, while affording relative adjustment 65 between the levers. The lever 50 is pivotally connected through a pin and slot connection 66 with a rod 67 threadedly secured at 68 to a block 69. This block is slidably mounted in transverse guideways 70 on the feed frame, and is actuated 70 in its guideways by an eccentric pin 71 engaging a vertical slot 72 in the block and formed on a disc 73 integral with an operating shaft 74, the latter having an operating lever 75. Adjustably threadedly secured to the rod 67 is a nut 76, and 75

interposed between the washer 77 engaging this nut and the lever 50, is a coiled spring 78. This coiled spring is set under a predetermined pressure to effect maximum loading of the low speed disc clutch 27, and constantly urges, through the levers 58 and 53, the clutch shipper ring 57 towards its clutch-applying position. When the operating lever 75 is swung to rotate the eccentric pin from its neutral position shown in Figs. 2, 6 and 8, to the left-hand dotted-line position indicated in Fig. 8, the block 69 is slid inwardly within its guideways, moving the rod 67 to swing the lever 50 inwardly about its pivot to effect swinging of the shipper yoke levers 59, 53 to release the low speed clutch 27 against the pressure of the coiled clutch-loading spring 78 and to apply the high speed clutch 18. When the lever 50 is swung into its high speed clutch-loading position, the link 48 connecting the lever 50 with the lever 40 moves the latter into a position out of engagement with the plunger 37, so that as the cam 35 rotates, the plunger remains idle within its guide bore. When the operating lever 75 is swung into its opposite position, the eccentric pin is rotated into the right-hand dotted-line position shown in Fig. 8, sliding the block 69 outwardly within its guideways, moving the rod 67 relative to the lever 50, thereby rendering the coiled clutch-loading spring 78 active to effect application of the low speed clutch 27. When the operating lever 75 is swung to rotate the eccentric pin into its neutral position indicated in full lines in Fig. 8, the rod 67 is moved to bring the end of the slot of the pin and slot connection into engagement with the pin on the lever 50 so that the coiled clutch-loading spring 78 is rendered inactive with the lever 50 in the position to release the low speed clutch 27. When the eccentric pin is positioned to move the rod 67 from the neutral position shown in Figs. 2 and 6 to the position wherein the coiled clutch-loading spring 78 acts on the lever 50 to effect application of the low speed clutch 27, the operator may rotate the handle 46 of the adjusting screw 45 to adjust the latter to swing the bell crank lever 42 about its pivot to vary the location of the fulcrum point 41 of the lever 40, and as a result, the engagement of the lever 40 with the cam-operated plunger 37 may be varied so that the range of swinging movement of the lever 40, and consequently that of the lever 50, may be varied, thereby to vary the time intervals of intermittent release of the low speed clutch 27.

It will be evident from the foregoing description that when the parts are in the neutral position shown in Figs. 2 and 6, the operating lever 75 may be swung to move the eccentric pin and rod 67 into the position wherein the coiled clutch-loading spring 78 effects loading of the low speed clutch 27; and when the fulcrum point of the lever 40 is properly positioned the plunger 37 remains idle within its guide bore, with the low speed clutch 27 held in applied position to effect continuous drive at the maximum low speed. In other words, when the low speed clutch 27 is continuously applied and the intermittent clutch release connections are in the proper position the lever 40 remains stationary as regards swinging movement about its pivot. When the handle 46 for the adjusting screw 45 is rotated, the intermittent clutch release connections are rendered active, so that as the cam 35 is rotated the plunger 37 is reciprocated to swing the lever 40 about its pivotal connection with the bell crank lever 42, and the swinging movement of the lever 40 is transmitted through the link 48 to the lever 50, swinging the latter about its pivot. Swinging movement of the lever 50 causes the shipper yoke lever 53 to swing therewith, thereby moving the clutch shipper ring 57 axially intermittently to apply and release the low speed clutch 27. At this time the shipper yoke lever 59 for the high speed clutch 18 is maintained in its released position. By adjusting the screw 45 to swing the bell crank lever 42 about its pivot, the fulcrum point 41 of the lever 40 may be varied so that its range of swinging movement effected by the reciprocating plunger 37 may be correspondingly varied. When the adjusting screw 45 is adjusted into its outermost position, the fulcrum point of the lever 40 is swung to move the lever about its pivotal connection with the link 48, so as to release entirely the lever 40 from the action of the plunger; and when the operating lever 75 is swung into its low speed clutch-applying position, the low speed clutch 27 is held applied by the coiled clutch-loading spring to effect a continuous low speed drive at the maximum low speed. By varying the position of the fulcrum point of the lever 40 between its innermost and outermost positions, any desired engagement of the lever with the plunger 37 may be afforded to obtain any desired time intervals of release of the low speed clutch 27. The coiled clutch-loading spring 78, when the clutch shipper yoke lever 53 is in loading position, is adapted to yield upon overloading of the low speed clutch 27. By turning the operating lever 75 of the eccentric operating means for the sliding block 69, the latter may be slid inwardly to swing the lever 50 about its pivot against the pressure of the coiled clutch-loading spring 78 to release the clutch shipper yoke lever 53 from the shipper ring 57 and to bring the clutch shipper yoke lever 59 into engagement with the clutch shipper ring 58 to apply the high speed clutch; the link 48, as the lever 50 is swung into this position, swinging the lever 40 away from the plunger 37 so that as the cam rotates, the plunger remains idle in its guide bore.

The general mode of operation of the improved coal cutting machine transmission mechanism is as follows: The machine may be moved rapidly over the mine floor at a high moving speed under the control of the lever 75 of the operating means for the high speed clutch 18, the feed cable being attached to an anchor at the face and the feed drum winding in the cable to drag the machine over the mine floor. When the machine is properly positioned with respect to the coal face, the high speed clutch is released and the motor 9 is reversed, so that the low speed gearing is driven in the proper direction to effect rotation of the feed drum in low speed winding direction, and the cutter chain is then connected in the usual manner to the motor, thereby to effect rapid circulation of the cutter chain about the margin of the cutter bar. The feed cable is then extended from the feed drum to the cutter bar 4, the cutter bar locking means then released, and the lever 75 is then operated to move the low speed clutch operating means into a position wherein the spring effects loading of the clutch 27; and as a result, the feed drum is rotated at a low speed to wind in the feed cable, thereby swinging the cutter bar about its pivot to make a horizontal sumping cut beneath the coal face. When the cutter bar is in the right-angle position shown in Fig. 1, the lever 75 is operated to effect release of the low speed clutch and the cutter bar is locked to 75.

the machine body by the locking means. The feed cable is then extended from the feed drum along the coal face to a suitable anchor located at the face in advance of the machine, and the operator then operates the lever 75 to again move the operating means for the low speed clutch 27 into the position wherein the coiled clutch-loading spring effects loading of the clutch; and as a result, the feed drum is rotated to wind in the feed cable to feed the machine at a relatively low cutting speed along the coal face to make a horizontal cut beneath the coal face. During the bar swinging and machine feeding operations, that is, when the bar is operated to effect its cutting function, the handle 46 may be operated to vary the relation of the intermittent release means for the low speed clutch with respect to the cam so that the low speed clutch may be intermittently released against the pressure of the coiled clutch-loading spring to effect an intermittent low speed drive, and by adjusting the handle 46 the time intervals of clutch release may be varied as desired, it being possible to effect drum rotation at a low speed between zero and a predetermined maximum low speed. During the cutting operation along the coal face, the lever 75 may be operated to effect release of the low speed clutch 27 against the pressure of the coiled clutch-loading spring, to apply the high speed clutch 19 to effect rotation of the feed drum in unwinding direction at a relatively high speed, thereby to place slack in the feed cable, it thereafter being possible to release the high speed clutch 18 and re-apply the low speed clutch 27 without changing the previous setting of the clutch release means; the lever 75 being operative to control both the low speed clutch and the high speed clutch.

From the foregoing, it will be evident that the feed drum 6 may be rotated in cable-winding direction through a wide range of low feeding speeds between zero and a predetermined maximum low speed; and may be driven at a predetermined high speed in the opposite, unwinding direction. When it is desired to rotate the feed drum at a high speed in cable-winding direction, the motor 9 is reversed.

As a result of this invention, it will be noted that an improved transmission mechanism is provided for a coal cutting machine, whereby the machine may be fed through a wide range of low speeds and at a predetermined high speed, having improved controlling means whereby the drive may be shifted from low speed to high speed in an improved manner. It will further be noted that by the provision of the intermittent clutch-loading means for the low speed drive, embodying a coiled spring placed under a predetermined compression, together with means for intermittently releasing the low speed clutch, it is possible to obtain a low speed drive having a maximum load limit, the coiled spring yielding to permit clutch slippage when the low speed clutch is overloaded. It will still further be noted that by the provision of the improved controlling means for the clutches, and the improved loading means for the low speed clutch, it is possible quickly to shift from low speed drive to high speed drive, and thereafter back to low speed drive, without the necessity of resetting the loading means for the low speed clutch, the controlling means being operated by but a single manual control element. Other uses and advantages of the improved transmission mecha-

nism will be clearly apparent to those skilled in the art.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a transmission mechanism, high and low speed driving means embodying a high speed drive clutch and a low speed drive clutch, means for automatically intermittently applying and releasing said low speed clutch at predetermined time intervals including means adjustable for variably setting said clutch applying and releasing means intermittently to apply and release said clutch at different time intervals to vary the low speed drive, and manually operable means operatively connected to an element of said automatic means and selectively disposable in positions respectively to relieve said low speed clutch from the action of said automatic means and apply said high speed clutch, and to release said high speed clutch and render said automatic means effective automatically to apply and release said low speed clutch, in each such position and during transit between such positions maintaining the adjustment of said variable setting means unchanged whereby, following a period of high speed drive, there may be a direct return to the same intervals as before of automatic application and release of the low speed clutch.

2. In a transmission mechanism, high and low speed driving means embodying a high speed drive clutch and a low speed drive clutch, means for automatically intermittently applying and releasing said low speed clutch at predetermined time intervals including means for variably setting said clutch applying and releasing means intermittently to apply and release said clutch at different time intervals to vary the low speed drive, and manually operable means operatively connected to an element of said automatic means for relieving said low speed clutch from the action of said automatic means and for applying said high speed clutch, said manually operable means operable following an application of said high speed clutch to release said high speed clutch and render said automatic means effective automatically to apply and release said low speed clutch without changing the setting of said automatic means which varies the time intervals of automatic application and release of said low speed clutch, said manually operable means including a manual operating member common to both clutches.

3. In a transmission mechanism, a drive clutch, a clutch applying lever, a spring acting on said lever and set at a predetermined clutch loading pressure, means including devices for providing timed impulses and for transmitting the same to said lever for automatically swinging the latter against the pressure exerted by said spring for intermittently releasing said clutch at timed intervals, and manually operable means for rendering said automatic clutch releasing means ineffective and thereafter manually rendering said automatic means effective without changing the timing of said impulse-providing devices.

4. In a transmission mechanism, a drive clutch,

5 a clutch applying lever, a spring acting on said lever and set at a predetermined clutch loading pressure, means connected to said lever for swinging the latter against the pressure exerted by said 10 spring for intermittently releasing said clutch at timed intervals including a rotatable cam and a lever actuated by said cam and connected to said clutch applying lever, and means for varying the time intervals of clutch release including 15 means for adjusting the fulcrum point of said second mentioned lever, said fulcrum point adjusting means including an adjustable lever to which said second mentioned lever is pivotally connected and means for swinging said last mentioned lever about its pivot.

5. In a transmission mechanism, a drive clutch, a clutch applying member, means for yieldingly urging said clutch applying member toward clutch applying position comprising a spring acting 20 on said clutch applying member and set at a predetermined clutch loading pressure, means connected to said clutch applying member for automatically actuating the latter against the pressure exerted by said spring to effect intermittent release of said clutch at timed intervals, and manually operable means for rendering said automatic clutch releasing means ineffective and thereafter manually rendering said automatic means effective again with the same timed 25 intervals of automatic clutch release as before.

6. In a transmission mechanism, a drive clutch, a clutch applying lever, a spring acting on said lever for yieldingly urging the latter into clutch loading position, means acting against the pressure exerted by said spring for automatically swinging said lever intermittently to relieve the load on said clutch at predetermined timed intervals, and manually operable means for rendering said automatic clutch releasing means ineffective and thereafter manually rendering said automatic means effective without changing the timed 30 intervals of automatic clutch release.

7. In a transmission mechanism, a drive clutch, a clutch applying lever, a spring acting on said lever for yieldingly urging the latter into clutch loading position, means acting against the pressure exerted by said spring for automatically swinging said lever intermittently to relieve the load on said clutch at predetermined timed intervals including a continuously rotating cam and connections actuated by said cam and connected to said lever, and manually operable means operatively connected to said lever for rendering said automatic clutch load relieving means ineffective and thereafter manually rendering said automatic means effective without changing the timed intervals of clutch load release.

8. In a transmission mechanism, a drive clutch, a clutch applying lever, a spring acting on said lever for yieldingly urging the latter into clutch loading position, means acting against the pressure exerted by said spring for automatically swinging said lever intermittently to relieve the load on said clutch at predetermined timed intervals including a continuously rotating cam, a lever actuated by said cam and a link connecting said last mentioned lever to said first mentioned lever, and means for adjusting the fulcrum point of said second mentioned lever to vary the time intervals of clutch release.

9. In a transmission mechanism, a high speed gear train having a high speed terminal gear, a low speed gear train having a low speed terminal gear, said terminal gears rotating in relatively opposite directions, a driven member, a

clutch for connecting said driven member to said high speed terminal gear for rotating said member at a high speed in one direction, a clutch for connecting said driven member to said low speed terminal gear for rotating said member at a low speed in the opposite direction, means for automatically effecting release of said low speed clutch at timed intervals to effect intermittent rotation of said driven member and embodying means for varying the time intervals of clutch release, and manually operable means associated with said means for releasing the low speed clutch and applying the high speed clutch, and operative to thereafter effect release of the high speed clutch and to reapply said low speed clutch without changing the time intervals of automatic low speed clutch release.

10. In a transmission mechanism, high and low speed driving means embodying a high speed drive clutch and a low speed drive clutch, yielding means set at a predetermined clutch loading pressure for applying said low speed clutch and acting constantly to urge said low speed clutch toward applied position, means associated with said yielding means for automatically releasing said low speed clutch against the action of said constantly acting yielding means at predetermined time intervals, and manually operable means associated with said yielding clutch loading means and embodying at least a part of the latter for relieving said low speed clutch from the action of said automatic means and for applying said high speed clutch, said manually operable means operable following an application of said high speed clutch to release said high speed clutch and to render said automatic means active automatically to release said low speed clutch at said predetermined time intervals without changing the setting of said automatic releasing means and said time intervals of low speed clutch release.

11. In a transmission mechanism, a drive clutch, means for automatically applying and releasing said clutch at predetermined time intervals, said clutch applying means set at a predetermined clutch loading pressure, means associated with said automatic applying and releasing means for determining the time intervals of clutch application and release, and manually operable means associated with said automatic means operable to release said clutch from the action of said automatic means to release said clutch, said manually operable means thereafter operable to render said automatic means active automatically to apply and release said clutch without varying the setting of said associated means which determines the time intervals of clutch application and release.

12. In a transmission mechanism, a drive clutch, means for automatically applying and releasing said clutch at predetermined time intervals, said clutch applying means set at a predetermined clutch loading pressure, means associated with said automatic applying and releasing means for varying the time intervals of clutch application and release, and manually operable means associated with said automatic means operable to relieve said clutch from the action of said automatic means to release said clutch, said manually operable means thereafter operable to render said automatic means active automatically to apply and release said clutch without varying the setting of said associated means which varies the time intervals of clutch application and release.

13. In a transmission mechanism, high and low speed driving means including a low speed drive clutch and a high speed drive clutch, means set at a predetermined clutch loading pressure for automatically applying said low speed clutch at predetermined time intervals, means associated with said automatic clutch applying and releasing means for determining the time intervals of clutch application and release, and 5 manually operable means associated with said automatic means operable to relieve said low speed clutch from the action of said automatic means to release said low speed clutch and to apply said high speed clutch, said manually operable means operable following an application 10 of said speed clutch to release said high speed clutch and render said automatic means effective automatically to apply said low speed clutch without varying the setting of said associated 15 means which determines the time intervals of application and release of said low speed clutch.

14. In a transmission mechanism, high and low speed driving means including a low speed drive clutch and a high speed drive clutch, automatic applying and releasing means including means set at a predetermined clutch loading pressure for automatically applying said low speed clutch at predetermined time intervals and embodying means associated with said automatic applying 20 means for varying the time intervals of clutch applications, and manually operable means associated with said automatic means operable to relieve said low speed clutch from the action of said automatic means to release said low speed clutch and to apply said high speed clutch, said manually operable means operable following an application of said high speed clutch to release 25

30 said high speed clutch and render said automatic means effective automatically to apply and release said low speed clutch without varying the setting of said associated means which varies the time intervals of application and release of 35 said low speed clutch.

15. In a transmission mechanism, a drive clutch, a clutch applying lever, a spring acting on said lever for yieldingly urging the latter into clutch loading position, means acting against the pressure exerted by said spring for automatically swinging said lever intermittently to relieve the load on said clutch at predetermined time intervals including a continuously rotating cam, connections actuated by said cam and connected to said lever, and means for adjusting the action of said cam actuated means to alter said predetermined time intervals, and manually operable means operatively connected to said lever for moving the latter to render said automatic clutch-loading-relieving means ineffective and for thereafter rendering said automatic means effective again with the same timed intervals of clutch load release as previously.

16. In a transmission mechanism, a drive clutch, a clutch applying lever, means for automatically swinging said lever intermittently to relieve the load on the clutch at predetermined time intervals including means adjustable while said lever swinging means is in operation for altering said time intervals, and distinct means, also controllable while said lever swinging means is in motion, for swinging said lever to disconnect said first mentioned means and to move said lever completely to unload said clutch. 35
